UNITED STATES PATENT OFFICE.

RICHARD C. SCAIFE, OF CLEVELAND, OHIO, ASSIGNOR TO THE WHITE COMPANY, OF CLEVELAND, OHIO, A CORPORATION OF OHIO.

DESIGN FOR A STEERING-COLUMN SWITCH AND LAMP-CARRYING UNIT.

49,038.

Specification for Design.

Patented May 9, 1916.

Application filed February 8, 1915. Serial No. 6,854. Term of patent 7 years.

To all whom it may concern:

Be it known that I, RICHARD C. SCAIFE, a citizen of the United States, residing at Cleveland, in the county of Cuyahoga and State of Ohio, have invented a new, original, and ornamental Design for a Steering-Column Switch and Lamp-Carrying Unit, of which the following is a specification, reference being had to the accompanying drawing, forming a part hereof.

Figure 1 is a rear view; Fig. 2 is a front view; Fig. 3 is a side view; Fig. 4 is a side

view looking toward the opposite side, and Fig. 5 is a top plan view of a steering column switch and lamp carrying unit showing my new design.

I claim:

The ornamental design for a steering column switch and lamp carrying unit substantially as shown.

RICHARD C. SCAIFE.
